UNITED STATES PATENT OFFICE.

KENTON C. KUNKLE, OF LEBANON, OHIO, ASSIGNOR OF SEVEN-TENTHS TO ALLEN A. KUNKLE, WALTER S. DILATUSH, AND JOHN A. BONE, ALL OF SAME PLACE.

GRAIN-BINDER.

SPECIFICATION forming part of Letters Patent No. 463,219, dated November 17, 1891.

Application filed November 25, 1890. Serial No. 372,589. (No model.)

To all whom it may concern:

Be it known that I, KENTON C. KUNKLE, a citizen of the United States, residing at Lebanon, in the county of Warren and State of Ohio, have invented certain new and useful Improvements in Grain-Binders; and I do declare the following to be a full, clear, and exact description of the invention, such as will enable others skilled in the art to which it applies to make and use the same, reference being had to the accompanying drawings, and to the letters of reference marked thereon, which form a part of this specification.

My invention relates to certain improvements in that class of grain-binders in which the grain is carried against a yielding compress-finger and formed into a gavel, which becoming of sufficient size causes said compress-finger to yield, thus throwing the trip 20 and setting the binder mechanism into motion, and has for its object the provision of a simply constructed and efficient binder of the class above mentioned.

The invention consists in the construction 25 and combination of parts hereinafter described, and pointed out in the claims.

What I deem the best means for carrying the invention into practice is illustrated in the accompanying drawings, in which the several parts are referred to by letter, to enable me to explain the principles employed in my invention, and also in which I have shown so much of a grain-binder as is necessary to fully illustrate the several features of my invention.

In the drawings, Figure 1 is a plan view of my device. Fig. 2 is a transverse section taken at the lower end of Fig. 1. Fig. 3 is a transverse section on the line $x-x$, Fig. 1, looking in the direction of the arrow. Fig. 4 is a transverse section on line $y-y$, Fig. 1, looking in the direction of the arrow. Fig. 5 is a detail plan view of eccentric and co-operating parts. Fig. 6 is an elevation of the end gear. Fig. 7 is an elevation of a bolt for securing the packer-arm to the spiders. Fig. 8 is a perspective view of the compressor-base and bracket on which it is supported broken off from the machine. Fig. 9 is a sectional elevation showing the needle and compressor at

the moment the dog comes into engagement with the ratchet when the forward movement of the needle is to be begun. Fig. 10 is a view similar to Fig. 9, showing the needle partially elevated and the compressor at the point where its inward movement begins. Fig. 11 is an edge view of the link connecting the crank on the needle-shaft and the compressor-plate. Fig. 12 is a perspective view of a packer-hook detached. Fig. 13 is a similar view to Figs. 9 and 10, taken at the moment when the bundle is under greatest compression. Fig. 14 is a view showing the construction of the compressor and needle-arm just after the opening or return movement of the needle-arm begins. Fig. 15 is a view similar to Figs. 9, 10, and 13, showing the position of the parts when the compressor has dropped. Fig. 16 is a view similar to Fig. 15, showing the position of the parts just before the needle reaches its farthest rearward movement and when the pin on the compressor-plate is engaged and held under the lip-pawl and just prior to assuming the position for filling shown in Fig. 9.

In the several views of the drawings similar parts are designated by the same letter of reference.

A A' are the frame-bars for securing the binder to the harvester, and $z z' z^2$ are cross-braces between the same, the center one z' being extended as a bracket, as shown, to receive the compressor. z^3 is a short brace secured to bars A', affording an additional bearing for the needle-shaft and a bearing for the packer-shaft. The brace z^3 is secured to brace z' by a bar or rod z^4 , which stiffens and unites the braces.

X is the main end casting, having at its upper end two parallel rods S S', said rods supporting at their outer ends a journal-bearing K, in which the corresponding portion of the knotter-shaft R rotates. It is evident that with very small additional weight there may be added several suitable braces, as shown at Y^2 , to the said casting X, thereby greatly increasing its strength. Said main end casting is provided with two journal-bearings for the purpose of suitably mounting the knotter-shaft R, and the shaft T, extending from the

packer device to the end gear, and also to said casting is rigidly secured in the proper place the journal-pin H, upon which the sway-bar L rocks.

5 R is the usual shaft upon which are mounted parts not shown, viz: sheaf-ejectors and knotter mechanism, all as usual; and T is the shaft extending from the packer system to the end gear and carries the eccentric W, 10 which actuates the needle A², and upon which the clutch-pawl a² is mounted.

b b² are cranks rigidly secured to the respective shafts R T. Upon the wrists c and c² of said cranks are respectively mounted the washers a³ a⁵ and the anti-friction rollers g g², which travel reciprocatively through the respective slots q q', situated in either end of the swing-bar L. Said anti-friction rollers are sufficiently small to rotate upon the wrists 20 c c² as they bear against either side of said slots.

G is a pitman connecting the cranks b b² and transmits the power alternately with the sway-bar L from the shaft T to the shaft R. 25 x x' are spring-pins securing the anti-friction rollers and pitman to the wrists of the cranks, and x³ is a spring-pin securing the sway-bar to the journal-pin H. This mechanical movement is made the subject-matter of 30 Patent No. 447,075, granted to me on the 24th day of February, 1891.

W is an eccentric securely mounted upon and carried by the shaft T. Said eccentric carries the pawls a a², belonging to the trip mechanism, together with their spring g³, designed to throw the pawl a into engagement with the ratchet P, the part a of said pawl being placed upon one side of the eccentric to engage the ratchet-wheel and the part a² on 40 the opposite side to start the trip mechanism.

P' is a pitman connecting the strap on the eccentric W and the crank O of the needle-shaft, thereby giving the proper movement to the needle.

45 B² is a trip-spring surrounding the trip-rod Y, and bears one end against the projection T' of the frame and the other end against the set-nut C', the spring B² being regulated by said nut C'.

50 S³ is an arm of the trip-rod Y, passing through the slot p' in the brace Z, in which it reciprocates and engages the pawl a² to throw the pawl a from the ratchet P and disconnect the binding mechanism, or releases

55 by the action of the compressor-finger O² said pawl a², and permit the ratchet P to engage the pawl a and cause the binding mechanism to actuate. The outer end of said trip-rod Y is secured to the crank P², which is rigidly

60 secured to the rock-shaft U. On the opposite end of rock-shaft U from the crank P² is the arm V, to engage the stud d, which is rigidly secured to the link I. Said link I is so connected to the compressor-finger O² that

65 sufficient pressure against said compressor-finger will cause the stud d to raise the arm V and rock the shaft U sufficiently to release

the pawl a² and unlock the binder mechanism. The link I is loosely secured to the lug p on the needle by the wrist f and also connected in a like manner to the compressor-bar K² by the wrist f', causing the compressor-finger O² as the needle rises to first recede from the gavel and then move toward said gavel or needle and compress the sheaf as it is bound, and in so doing places itself in such a position as to cause the said compressor-finger to fall sufficiently low as to allow the sheaf to be discharged and then to return to its position to receive the next following gavel, 80 all of which is hereinafter fully explained.

The compressor-bar K², to which the finger O² is secured by the bolt t, is provided with the holes r r to allow for different sizes of sheaves and with the slot h, by which it is mounted upon the stud k, provided with the nut l to secure said compressor-bar thereto and allowing said bar K² to both rock and reciprocate upon said stud k. The compressor-bar is also provided with the pin m, upon which may be mounted an anti-friction roller, if so desired, said pin m being engaged by the cam-ledge n upon the main frame, the purpose of which is hereinafter explained.

On the outer edge of the bracket Z³ is loosely secured the lip-pawl a⁴, provided with the spring b⁴. Said lip-pawl is situated so as to engage the pin m and prevent the finger O² from being thrown as the compressor recedes from the gavel, as hereinbefore referred to, as will be seen in Fig. 10; but after the finger O² has been thrown in the manner spoken of and to be described the said lip-pawl a⁴ yields to the pressure of said pin m as it returns and allows said finger to pass to its former position, as will be readily seen in Fig. 16.

E is the usual shaft to which the power is applied from the harvester and which gives motion to the packer mechanism.

F F' F² F³ are eccentrically-mounted spiders 110 rigidly secured to their respective shafts, and carry, in the manner illustrated, the packer-hooks N. Said hooks are secured to the spiders by bolts e in such a manner that the bolts e are rigidly fixed to arms of said spider and rotatably mounted in their respective journal-bearings in said hooks.

Upon the inner end of the shaft E is rigidly secured the spider F, having to the outer end of each arm of said spider a bolt e securely fixed, as before mentioned.

At sufficient distance to allow the packer-hooks N to be properly mounted as to operate unmolested is another similar spider F', with similar fixtures securely mounted on one end of the short packer-shaft E' in such a manner that these two spiders rotate upon different centers in order to give the proper movement to the packer-hooks N, which travel between and are carried by said eccentrically-mounted spiders. Each packer-hook is provided with a projecting arm N' sufficient in length to allow the two journal-bearings situated therein to be the same distance apart as

the center of the two spiders are apart. Said projection is constructed in such a manner as not to travel in the same plane as the body of the packer-hook N, and it will be readily seen that by this arrangement it is possible for the packer-hook to be much longer than if it and the projection traveled in the same plane. These projections extend from the body of the packer-hook at an angle somewhat greater than a right angle, experiments having proved that the best results are attained thereby. It is evident that by changing the center of either eccentric spider either up or down that any desired movement of the packer-hooks may be obtained.

The entire packer mechanism consists of two such movements as the one just described, one mounted on each side of the needle. On the spider F³, which is loosely mounted on the inner end of shaft T, the ratchet P is securely fixed, by means of which the binder mechanism is actuated, as already explained.

By using the number of packer-hooks herein illustrated I am enabled to give the same speed to the packer-shaft as is given to the needle and knotter-shafts, giving as effective action upon the cut grain, and at the same time avoiding all complicated parts for changing the time from the packer-shaft to the needle and knotter shafts. I also avoid thrashing out the grain and breaking the straw, as it is evident that the faster the packer-hooks travel the greater is the force with which they beat against the grain, and it will be seen that the strain is taken from the needle-point in forcing its way through the tangled and clogged grain as the packer-hooks move with the needle and assist it in its efforts to part the grain.

10 The trip device herein described will set the binder mechanism into immediate action at the same moment that the gavel presses with sufficient power to throw the trip. This is not the case in binders heretofore made; 45 but, on the contrary, the packers of such binders often carry considerable grain into the gavel after the trip has been thrown and before the binder is set in motion, frequently causing the binder to become choked. The 50 needle-shaft A* with its three bearings is very securely mounted and, as seen, is very short in length.

One of the novel features of my invention is throwing and raising the compressor-finger by the backward motion of the needle, which is accomplished as follows: The slot h in the compressor-bar K² causes the said bar to assume such a position with reference to the link I that as the needle returns the link I 60 raises the inner end of said compressor-bar, causing the finger O² to be lowered sufficiently to allow the sheaf to pass out, and just before the needle has ceased its backward motion the stud d on the inner side of link I is engaged by a suitable stop, preferably the arm V on the rock-shaft U, and changes the direction of power of the link I upon the com-

pressor-bar in such a manner as to return the finger O² to its former position, as will be understood from the views shown in Figs. 9, 10, 13, 14, 15, and 16. To fully insure the downward movement of the finger O², the forward end n' of the cam-ledge n is so shaped and located as to engage the pin m and act as a starter. It is also evident that the sheaf will assist in throwing the finger O² back sufficiently to allow it to pass out of the binder. It is also evident that the receding movement of the compressor-finger O² is an advantage, as it allows the needle its full power to rise 80 through the grain. Said finger does not move toward said needle until said needle has separated the grain and has full power to compress the grain against it.

It will be noticed that the weighty portion 85 of the mechanism is located near the center of the binder instead of at one end, as is commonly the case, so that in shifting or adjusting the binder for longer or shorter grain the weight on the end of the tongue of the harvester will be unchanged.

Having thus described my invention, what I claim, and desire to secure by Letters Patent, is—

1. In a grain-binder, packer-hooks N, having projections N' offset therefrom, so as not to travel in the same plane with the body of the packers, in combination with spiders on which the packers are mounted, as and for the purpose set forth.

2. The combination of a pair of spiders eccentrically mounted, the packers N, having the rigid projections N' offset therefrom so as to travel in a different plane from the one traversed by the main body of the packers, 105 an end of the packer being mounted upon an arm of the spider, and the outer end of its projection being connected to an arm of the other spider, substantially as and for the purpose set forth.

3. The combination of a pair of eccentrically-mounted spiders, the packers N, having the rigid projections N' offset therefrom, so as to travel in a different plane from that traversed by the main body of said packers, 115 and the bolt e, rigidly secured to the spider-arms and having journal-bearings in the projections, as set forth.

4. The combination, with a binder-needle and a packer-spider, of a ratchet-wheel secured to said spider, an eccentric mounted on the end of a shaft and lying beside the ratchet-wheel and strap for operating the said needle, a dog attached to the eccentric and engaging the ratchet-wheel, and a trip mechanism for 125 throwing the dog, as set forth.

5. The combination, with a binder-needle and a packer-spider, of a ratchet-wheel secured to said spider, an eccentric and strap for operating the needle, a dog attached to the 130 eccentric and engaging the ratchet-wheel, a trip-pin for releasing the dog at one point in the revolution of the eccentric, a rod or arm connected with the trip-pin at one end, and a

means located at the opposite end of said rod or arm for moving the rod and trip-pin, as set forth.

6. The combination, with a binder-needle, of a compressor having a slotted base or bar riding on a stud on the binder-frame, and a link connecting the said base with a projection on the needle-shaft, said link having a bearing against a stop on the binder-frame, as set forth.

7. The combination, with a binder-needle, of a compressor having a slotted base or bar riding on a stud, and a pin on said base working under a ledge, said ledge and stud being fixed on a rigid portion of the frame, and a link connecting said base with a projection on the needle-shaft, said link having a stud for engaging a stop on the fixed frame, as set forth.

8. The combination, with a binder-needle, of a compressor having a slotted base and a pin upon it, a bracket on the binder-frame

having a stud on which the base rides and a ledge under which the pin works, and also being provided with a spring lip pawl, against which the pin abuts, and a link connecting said base with a projection on the needle-shaft, as set forth.

9. The combination, with a binder-needle and compressor, of a link connecting the compressor to a projection on the needle-shaft, said link having a pin or projection to engage a stop on the binder-frame and change the direction of power of the link upon the compressor and bring the latter back to its normal position to receive the cut grain, as set forth.

In testimony whereof I affix my signature in presence of two witnesses.

KENTON C. KUNKLE.
